UNITED STATES PATENT OFFICE

EDGAR D. MOORE, OF MANSFIELD, OHIO, ASSIGNOR TO THE OHIO BRASS COMPANY, OF MANSFIELD, OHIO, A CORPORATION OF NEW JERSEY

TROLLEY POLE

Application filed March 6, 1930. Serial No. 433,676.

My invention relates to a trolley pole and its object is to improve the electrical conductivity of the present type of pole and its contact with supporting devices.

5 The present trolley poles used for supporting a current collector in contact with trolley wire are made of steel and are as thin cross section as possible to secure lightness, therefore they are of relatively high resistance to a 10 flow of current.

The current demand on cars is considerably on the increase and no provision has been made to improve the electrical conductivity of the poles or the contact with the pole supporting device commonly known as a trolley base.

20 My invention resides in the new and novel construction, combination and relation of the various parts hereinafter described and shown in the accompanying drawing;—

Fig. 1 is an interrupted view in elevation of my invention and in partial section.

Fig. 2 is a section on the line 2—2 of Fig. 1.

Fig. 3 is a section on the line 3—3 of Fig. 1.

25 Fig. 4 is a view of the large or lower end of the pole.

Fig. 5 is a view of the upper or small end of the pole.

Fig. 6 is a modification of my invention 30 later described.

In the preferred embodiment of my invention, I use a pole member 1 of required length and diameter, of tubular cross section and usually tapered. The pole is preferably of 35 seamless drawn or rolled construction although it may be butt or lap welded under some conditions.

40 In order to increase electric conductivity of the pole I position within the pole a conductor 2 preferably of copper which may be of solid or flexible wire and bare or insulated although I prefer the former. The ends 3 and 4 of the member 2 are brought to the ends of the pole 1 and secured thereto by means of 45 the welds 5 and 6 respectively. The welds are made preferably with copper or copper base alloy and may be accomplished by means of the oxy-acetylene flame or the electric arc or by brazing.

50 It is not new to connect the current collec-

tor or its immediate support directly to the trolley base by means of a conductor, but this method is of distinct disadvantage because it is frequently necessary to change a trolley pole while the car is in service and such 55 changes must be made as rapidly as possible and if it is necessary for the car operators to be obliged to not only remove the pole from its trolley base but also disconnect and connect the cable from the trolley base considerable 60 time is involved in excess of that which would be required in changing a pole of my invention.

To further increase the efficiency of the pole I apply to the outer surface of the lower 65 end a coating of copper or other high conductivity material which is engaged by the clamps of the trolley base. This coating may be applied by electroplating or by metal spray or by dipping the end of the pole in molten 70 metal. This coating is represented by the numeral 7 in the drawings and is brought across the end face of the pole as shown at 8 and has electrical contact with the conductor 2 which may be brought about by bringing the weld 75 6 across the end of the pole 1 as shown at 9.

It is quite evident that if desired a coating 10 may be applied to the outer surface at the small end of the pole the same as described at the large or lower end and connected at 11 80 to the conductor 2 and it is also quite evident that the coating may be applied to the inner surface of the pole adjacent the ends thereof.

In Fig. 6 I have shown a modification in that the pole is provided with a lining 12 of 85 copper or other non-ferrous metal in union with the inner surface of the pole. This may be accomplished by forming the pole of a rod of bi-metal or of coating the inside of the pole of steel by means of molten metal in contact 90 therewith.

Having disclosed my invention and knowing that others may create modifications thereof, I wish to be limited only by my 95 claims.

I claim:—

1. A trolley pole comprising a tubular member of ferrous metal, a conductor of copper within the member and extending from end to end of the member and having its ends 100

welded to the inner surface of the member at its ends, a coating of copper applied to the outer surface of the ends of the member and extending back from the ends and extending across the end faces of the member and connected to the conductor.

6 2. A trolley pole comprising a tubular member of ferrous metal, means extending longitudinally through the member from end to end and having its ends welded to the inner surface of the member by means of attaching metal, the attaching metal extending across the face of the member at one end.

10 3. A trolley pole comprising a tubular member of ferrous metal, means extending longitudinally through the member from end to end and having its ends welded to the inner surface of the member by means of attaching metal, the attaching metal extending across the face of the member at one end, a coating of non-ferrous metal on the outer surface of the member at one end and electrically connected to the conductor by said attaching metal.

15 25. 4. A trolley pole comprising a tubular member of ferrous metal with a conducting member therein of copper extending from end to end of the tubular member and the two secured together at their ends and a layer of non-ferrous metal mechanically secured to the pole adjacent an end and having direct electrical connection with the pole and with the conducting member.

30 35. 5. A trolley pole comprising a tubular member of ferrous metal with a conducting member therein of copper extending from end to end of the tubular member and the two secured together at their ends, a non-ferrous conducting member secured to the outer surface of the tubular member at its end and having an electrical connection with the copper conducting member other than that through the ferrous member.

40 45. 6. The method of manufacturing trolley poles comprising the steps of forming a seamless tapered tube of ferrous material, positioning a conducting member of non-ferrous material within the tubing and then welding the ends of the non-ferrous member to the surface of the tubing adjacent its ends.

50 55. 7. The method of manufacturing trolley poles comprising the steps of forming a seamless tapered tube of ferrous material, depositing a coating of non-ferrous metal upon the outer surface of the pole adjacent its end, positioning a conducting member of copper within the tubing and then uniting the ends of the non-ferrous member to the surface of the tubing adjacent its ends and to the coating.

60 In testimony whereof I affix my signature.
EDGAR D. MOORE.
